US00D864271S

(12) **United States Design Patent** (10) **Patent No.:** **US D864,271 S**
Lai et al. (45) **Date of Patent:** **** Oct. 22, 2019**

(54) **ROBOT**

(71) Applicants: **BEIJING JINGDONG SHANGKE INFORMATION TECHNOLOGY CO., LTD.**, Beijing (CN); **BEIJING JINGDONG CENTURY TRADING CO., LTD.**, Beijing (CN)

(72) Inventors: **Meike Lai**, Beijing (CN); **Qiming Wang**, Beijing (CN)

(73) Assignees: **BEIJING JINGDONG SHANGKE INFORMATION TECHNOLOGY CO., LTD.** (CN); **BEIJING JINGDONG CENTURY TRADING CO., LTD.** (CN)

(**) Term: **15 Years**

(21) Appl. No.: **29/637,127**

(22) Filed: **Feb. 14, 2018**

(30) **Foreign Application Priority Data**

Aug. 18, 2017 (CN) 2017 3 0381609

(51) LOC (12) Cl. **15-99**

(52) U.S. Cl.

USPC **D15/199**

(58) **Field of Classification Search**

(57) **CLAIM**

The ornamental design for a robot, as shown and described.

DESCRIPTION

FIG. 1 is a front perspective view of a robot showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The broken lines illustrate structure or features of the robot which form no part of the claimed design.

1 Claim, 7 Drawing Sheets
